UNITED STATES PATENT OFFICE

EDMUND A. SKOWRON, OF PITTSBURGH, PENNSYLVANIA, ASSIGNOR TO WOODINGS-VERONA TOOL WORKS, OF VERONA, PENNSYLVANIA, A CORPORATION OF PENNSYLVANIA

RAIL ANCHOR

Application filed December 30, 1930. Serial No. 505,504.

This invention relates to rail anchors, and more particularly to those comprising a single piece of bar steel bent to form an intermediate tie-engaging loop, with a hook at one end and a jaw at the other end adapted to engage the edge of a rail base, and so shaped as to require distortion of the anchor in order to bring the hook and jaw into engagement with the upper side of the rail.

An object of the invention is to provide a one-piece rail anchor adapted to have constantly resilient engagement with the upper and lower side of the rail base. Another object is to provide the anchor with a depending loop adapted to engage a tie, the opposite ends of the anchor being bent oppositely out of the plane of the loop and adapted to bear on the upper side of the rail base.

Another object is to produce a one-piece rail anchor having its ends formed into a hook and a jaw adapted to engage the opposite edges of the rail base, said hook and jaw being bent laterally and oppositely out of the plane of the intermediate portion of the anchor and adapted to be distorted as the anchor is driven transversely across the rail to gripping position thereon, the opposite positioning of the hook and jaw resulting in a torsional constant grip on the rail, the two ends tending to twist the anchor in opposite directions.

Other objects and advantages will be apparent to those familiar with the art.

Referring to the drawings, Fig. 1 is a perspective view of the anchor before application to the rail R; Fig. 2 shows the anchor as preliminarily applied to a rail only with the jaw end engaged; Fig. 3 shows the anchor as preliminarily applied to a rail and rotated from the position of Fig. 2 ready to be driven to final position on the rail; Fig. 4 is an end view of the anchor as shown in Fig. 3; Fig. 5 is a side view of the anchor after application to a rail; and Fig. 6 is an end view of the anchor as applied to the rail and abutting the tie.

Rail anchors are applied to railway rails for the purpose of preventing creeping of the rails in the direction of train travel. Such devices and their general purposes are well

known in the art and need not be described in general. The invention here involved relates only to improvements in structure of a device that is generically old in the art.

The particular device constituting the present invention consists of a single piece of bar steel, which is preferably round. A suitable length of the bar is cut off, bent hot by suitable dies and presses to the desired shape, and then heat-treated. The completed anchor comprises an intermediate loop L, adapted to depend under the rail to which the anchor is attached, and to form an abutment for a tie T in the track, as shown in Fig. 6. The two ends of the bar are bent to form a hook H and a jaw J adapted to engage respectively the opposite sides of the rail base.

The hook H as shown in Figs. 3 and 5 comprises a substantially straight horizontal portion 2, an upright portion 3 and a terminal inturned portion 4, bent back at an angle to the portion 2. The upright portion 3 of the hook is bent laterally with respect to the general plane of the loop portion L.

At the other end of the bar is formed a laterally extending portion 5 in substantial alignment with the portion 2 above referred to, an upright portion 6, and a bent back terminal portion 7, all constituting the jaw J. The terminal portion 7 of the jaw is bent laterally with respect to the plane of the loop L, in a direction opposite to that in which the hook H is bent. Thus the hook and jaw are bent oppositely out of the plane of the loop L.

The clearance of hook H is sufficient to permit it to slip over the edge of a rail only when the hook is in substantially vertical position.

Likewise the jaw J, when in a vertical plane as shown in Fig. 2, is wide enough to freely receive an edge of the rail base, but when the anchor is rotated on its longitudinal axis sufficiently to bring the jaw J into position to pass over the edge of the rail base, the effective clearance of the jaw is not sufficient to receive the rail base. Consequently, for both the jaw and hook to engage the rail base the anchor must be distorted, bending the

jaw or hook, or both, or the body portion between them out of normal position.

The anchor is applied by slipping it under the rail with the loop nearly flat against the bottom of the rail base, as shown in Fig. 2. 5 This permits the jaw to engage one side of the rail base, the hook being then substantially parallel with the under side of the rail. With the rail base extending to the innermost parts of the jaw J, the end of the hook H is positioned beyond the opposite edge of the rail base, as shown in Fig. 2. By then rotating the anchor on its longitudinal axis as far as it is permitted to go by the clearance of the jaw J, the end of the hook H is brought up to the position shown in Fig. 3. It will just clear the corner of the rail base, and will be positioned obliquely with respect to the bottom of the rail, and the plane of the loop of the anchor will be positioned in a plane oblique to a perpendicular transverse section of the rail, as shown in Fig. 4.

The anchor is then struck on the hook end thereof with a spike maul, or other tool, to drive it transversely across the rail. As the hook rides up on the rail base it tends to rotate the anchor on its longitudinal axis. This rotative tendency is resisted by the jaw J, which has already been turned in that direction as far as it can go without distortion. 30 The result is that driving the hook onto the rail base to the position shown in Fig. 5 distorts the anchor. When therefore the anchor has been driven home it is seated on the rail with a strong resilient pressure on the upper side of each edge of the rail base, and with a fulcruming pressure on each side of the under face of the rail base.

The anchor is thus applied under a permanent strain, so that both ends thereof will be constantly urged downward on the top of the rail base, and the portions 2 and 5 are constantly urged upward against the under side of the rail base.

As the rail tends to creep forward in the direction shown by an arrow, Fig. 6, the tendency will be to cant the bottom of the anchor rearwardly with respect to the rail, and that tendency will increase the shackle grip of the hook on the rail.

It has been found from practice that an anchor constructed according to the foregoing description will give a very strong grip on the rail, which will be materially increased 55 due to the canting action of the abutment of the loop against the tie. Due to the length of the bar and the proportioning of the bends therein, the distortion incident to application of the anchor to the rail is so distributed that no part is strained beyond the elastic limit of the steel. Consequently it retains the full strength and usefulness after one or more applications. When it is desired to take the anchor off the rail a blow of a spike maul

or the like on the jaw end thereof will release it.

This anchor has the advantage of being made from a single piece of standard shaped bar metal, without any loss due to scrap, and 70 without the necessity of any punching or forging operations. It may be readily applied without special tools, and as easily removed.

I claim:

1. A rail anchor adapted to resiliently engage a rail base and consisting of a single bar of spring steel bent to form a rail-base engaging hook at one end, a depending intermediate loop adapted to contact with a tie, 80 a rail-base engaging jaw at the other end, the bar being bent to turn the said hook and jaw portions laterally oppositely out of the plane of the intermediate loop to an extent requiring distortion of the anchor to permit its application to the rail base, the jaw being adapted to engage preliminarily one side of the rail base and to permit turning the anchor to bring the hook into engagement with the upper corner of the opposite side of the rail base, 90 the hook being shaped to cause rotation of the loop and distortion of the anchor as the hook is driven onto the rail base.

2. A rail anchor of the class described consisting of a single bar of spring steel bent to 95 form a rail-base engaging hook at one end, a depending intermediate loop, a rail-base engaging jaw at the other end, the bar being bent to turn the said hook and jaw portions laterally oppositely out of the plane of the intermediate loop and spaced to require bending the hook and jaw back toward said plane to permit application of the anchor to a rail.

3. A rail anchor consisting of a single bar of spring steel bent to form a rail-base engaging hook at one end, a depending intermediate loop adapted to contact a tie under a rail, a rail-base engaging jaw at the other end, the bar being bent to turn the said hook and jaw portions laterally oppositely out of the plane of the intermediate loop whereby to require distortion of the anchor to permit its application to a rail, the jaw being adapted to engage one side of the rail base and to permit longitudinal rotation of the anchor thereafter 105 before bringing the jaw end into contact with the upper side of the said rail base and the hook into position to ride up on the opposite side of the base, the hook being adapted to rotate the anchor in reverse direction as it is driven on the rail base, whereby to distort the bar and effect a resilient grip on each side of the rail base.

4. A rail anchor consisting of a single bar of spring steel bent to form a rail-base engaging hook at one end, a depending intermediate loop adapted to contact a tie under the rail, a rail-base engaging jaw at the other end, the bar being bent to turn the said hook and jaw portions laterally oppositely out of the plane 110 125 130

of the intermediate loop to an extent requiring distortion of the anchor to permit its application to a rail, the jaw having its terminal end turned over laterally and backwardly to bear upon the upper side of the rail base when the hook is seated on the opposite edge of the rail, said terminal end of the jaw being adapted to be sprung upward when the hook is driven onto the rail base.

5 10 In testimony whereof I sign my name.
EDMUND A. SKOWRON.
